UNITED STATES PATENT OFFICE.

MCKENDREE H. MCKEE, OF SOUTH BEND, INDIANA.

REINFORCED CONCRETE CONSTRUCTION.

1,142,109.

Specification of Letters Patent.

Patented June 8, 1915.

Application filed January 9, 1913. Serial No. 741,084.

To all whom it may concern:

Be it known that I, MCKENDREE H. MCKEE, a citizen of the United States, residing at South Bend, in the county of St. Joseph and State of Indiana, have invented new and useful Improvements in Reinforced Concrete Constructions, of which the following is a specification.

This invention relates to improvements in concrete wall construction, and more particularly to the reinforcement of concrete walls.

The invention proposes a reinforcement which may be made up of a number of units. The essential characteristics of each unit are that it is a separate article of manufacture and sale; that it is independently adjustable as to its longitudinal extent; that it is originally set up in preadjusted position; and that it forms a permanent element of the metallic superstructure about which the concrete wall is to be built.

The purpose of the reinforcing units are to provide a reinforcement which may be conveniently and quickly adapted to the needs of the structure both as to the extent of the reinforcement required in particular cases and as to the dimensions of the spaces in which the reinforcement is to be fitted. The device is particularly adapted for the rapid and economical construction of small cement buildings, such as garages, barns, and poultry houses.

An embodiment of the invention and examples of practical applications thereof are shown in the accompanying drawings, wherein:

Figure 1 is a view showing a partially completed building in cross section, and embodying elevational illustrations of a side and front wall; Fig. 2 is a detail sectional view illustrating one form of a corner joint between two reinforcing units at adjoining ends of angularly related walls; Fig. 3 is a detail sectional view illustrating a channel seat for the reinforcing units; Fig. 4 is a view, partly in side elevation and partly in section, showing the skeleton work of a side wall of the structure shown in Fig. 1; Fig. 5 is a detail sectional view to a some-

what enlarged scale, on the line 5—5 of Fig. 4; Fig. 6 is a detail horizontal sectional view of a wall in the course of construction, with the reinforcing units incorporated therein; Fig. 7 is a fragmental elevation of 55 a finished wall in which the reinforcing units are incorporated.

Similar characters of reference designate corresponding parts throughout the several views.

The metallic reinforcement for the concrete wall includes essentially a number of reinforcing units which are adjustable as to their longitudinal extent. In the embodiment disclosed, a reinforcing unit comprises a pair of parallel side bars 1 in the form of T-irons, which are arranged in confronting relation, an intermediate bar 2 of shorter length than the side bars, and upper and lower pairs of links 3 and 4, pivoted to 70 the respective side bars 1 somewhat adjacent the upper and lower ends thereof, and pivotally connected to one another at their mutually adjacent ends, as at 5. The bar 2 is formed with slots 6 and the pivots 5 of the 75 links 3 and 4 pass through the slots. The links of each pair are arranged adjacent opposite faces of the bar 2 as clearly shown in Fig. 5, and are pivoted at relatively opposite sides of the central flanges of the bars 1. 80

When two or more of the reinforcing units are arranged in adjoining relation, it is preferred to positively connect them. Thus, Fig. 5 shows three units adjoining in a single wall and the bars 1 are placed back to 85 back and are connected by rivets 7. Where the units adjoin at a corner of the building, the connection shown in Fig. 2 may be employed, the bars 1 being so arranged as to form a corner wall angle of ninety degrees. 90 In this case the central flange of one of the bars 1 is riveted or otherwise secured as at 8, to the outer side flange of the other bar, and the bars may be positively held in the desired relation by the use of sleeves 9 surrounding the rivets or bolts of the connecting seam.

The building shown generally in Fig. 1 has a foundation of concrete, the upper face of which is grooved to receive channel bars 100

10 which form positive retaining seats for the reinforcing units. To illustrate applications of the invention, a portion of the front wall of this building is taken up by a 5 door 11 and a window 12. The foundation is cut away to accommodate the door and the window 12 seats upon a channel bar 10. Somewhat narrow spaces intervene between the side walls, and the window and door 10 which they adjoin. In each of these spaces a reinforcing unit of the construction described is arranged. The space at the left side of the wall is narrower than the space at the right, and the units are in each instance 15 adjusted, in respect of their longitudinal extent, to conform to the extent of these spaces. This figure also shows the utility of the units as part of the superstructure, which may include other metallic elements, such, for instance, as the horizontal bar 13 which extends between the units and, in the construction shown, forms a common 20 lintel for the window and door. Between the bar 13 and the roof or ceiling there is a rectangular 25 inclosure 14, which may or may not, according to choice, be taken up by a reinforcing unit, or units.

Fig. 4 shows details of the side wall construction of the building illustrated in Fig. 1, wherein a number of units are arranged in immediately adjoining relation. The units at the ends of the side walls are joined to the units at the ends of the front and rear walls by the corner joints shown in 30 Fig. 2, and already described, and the units of each side wall are connected in their adjoining relation by the fastening devices 7. For convenience of illustration, this figure shows one unit adjusted to its maximum 35 extent, and an adjoining unit adjusted to have a less extent. The adjustment of the units is effected by moving the pivots 5 in the slots 6, a movement of the pivots toward one another reducing the longitudinal 40 extent of the units and a movement of the pivots away from one another increasing the longitudinal extent of the units.

Fig. 4 also illustrates a further feature of utility of the construction, in that it 45 enables the roof elevation or inclination to be determined by suitably inclining the upper faces of the side wall portions of the foundation. In such a case, the bars 1, owing to the fact that their mutual connections are pivotal or flexible, adjust themselves to the inclination of their seats, as is obvious.

In most cases, the bars 1 will require a 50 parallel relation, but in some instances it might be desirable to incline one bar relatively to the other. Obviously, this can be effected by suitably differentiating the angle formed by the links of one pair from the angle formed by the links of another pair.

The upper ends of the bars 1 may, if desired, be utilized to support the cross bars or beams 15 by which the ceiling or roof 16 is supported. Such an arrangement is shown in Fig. 1.

Any desired method of wall molding may 65 be employed. Figs. 1 and 6 show a method which is quite well known, wherein planks 17 are progressively set up in confronting relation and the space between them is filled with concrete which is firmly tamped. 70 When the concrete sets the planks are removed and the holes left by their retaining bolts 18 are suitably filled. In practising this method, the planks 17 may be placed immediately adjacent the bars 1, as shown, 75 in which case the side edge faces of said bars are flush with the concrete (Fig. 7), or the planks may be spaced from one another to an extent greater than the maximum thickness of the reinforcing units, so that 80 the concrete will wholly conceal said units.

The units themselves may be made in various sizes and a suitable number and selection may be furnished in each instance to accommodate the needs of the building 85 under construction. They are readily adaptable for the reinforcement of a wall as an entirety as in Fig. 4, or of isolated portions of the wall as in Fig. 1, when a series of units in adjoining relation are employed, 90 they may all be adjusted to have the same extent, or, if circumstances necessitate, some of the units may be adjusted to have greater or less extent than others. In many 95 cases, especially where the buildings are small, the units may, as shown, be employed to make up the superstructure of the building, and in other cases they may be employed as reinforcing elements *per se*, and not as parts of a metallic superstructure or 100 skeleton.

Having fully described my invention, I claim:

1. A reinforcing unit for use in concrete 110 wall construction, comprising a pair of bars, an intermediate slotted adjusting bar, and links pivoted to the first named bars and to one another, the mutual pivots of the links being arranged in the slots of the adjusting bar.

2. A reinforcing unit for use in concrete 115 wall construction, comprising a pair of bars, an intermediate slotted adjusting bar, and links pivoted to the first named bars and to one another, the links being arranged in upper and lower pairs, the mutual pivots of the links being arranged in the slots of the adjusting bar.

3. A reinforcing unit for use in concrete 120 wall construction, comprising a pair of T-bars arranged in confronting relation, an intermediate slotted adjusting bar, and links arranged in upper and lower pairs,

the links of each pair being pivoted at relatively opposite sides of the central flanges of said T-bars and being pivoted to one another at their adjoining ends, the mutual 5 pivots of the links being arranged in the slots of the adjusting bar.

In testimony whereof I have hereunto

set my hand in presence of two subscribing witnesses.

McKENDREE H. MCKEE.
